UNITED STATES PATENT OFFICE.

HERMANN OBERSCHULTE, OF ESSEN-ON-THE-RUHR, GERMANY.

DOLPHIN PILE.

Application filed April 19, 1927, Serial No. 185,031, and in Germany March 4, 1926.

An important point in connection with the construction of dolphin piles is that, in addition to great mechanical strength, they should also possess a maximum of elasticity, so as to be able to absorb the kinetic energy of vessels moored alongside. Many dolphin piles as hitherto constructed have, however, not met with any great success because they lack this requisite elasticity.

The present invention obviates this drawback inasmuch as the dolphin pile is made of sheet metal pile members rammed together to form a hollow structure. As a result of the numerous joints between the individual pile members a certain mobility is produced and, consequently, a high degree of elasticity.

Obviously the choice of the individual sections must be made with regard to the object in view. As a rule, considerable value will be attached to the production of a structure having a smooth surface free from projecting locking parts, for which reason the sections used must be such that the joints are situated either in the neutral axis, or on one side throughout. If a particularly strong pile is required, it is advisable to employ so-called box sections.

After ramming the sheet piling may also be strengthened by anchoring in the ground. Further, it is advisable, though not absolutely necessary, to fill up the cavities of the sections and the interior of the structure with a filling material such as sand, concrete or the like. Whether and to what extent concrete filling is employed in individual cases will depend on the intended use.

A cover or capping may be used to close the top of the structure. Said capping is preferably of ferro-concrete, the reinforcing irons of which are anchored to the upper part of the sheet piling. The rings and the like, required for mooring the vessels, may be easily attached to said capping in any convenient manner.

By way of example, two constructional forms of dolphin pile in accordance with the invention are illustrated diagrammatically on the accompanying drawing to which reference will now be made.

Fig. 1 is a partial plan view of one form to a sufficiently large scale to show the interconnection of the individual pile members of the structure.

Fig. 2 is a plan view of this form to a smaller scale and illustrates the closed structure formed by the interlocked pile members.

Figs. 3 and 4 are views, similar to Figs. 1 and 2 respectively, of the second illustrated form of the invention.

Fig. 5 is an elevation of a completed pile with parts in section.

As shown, a plurality of sheet metal pile members, denoted *a* in Figs. 1 and 2 and *b* in Figs. 3 and 4, are rammed in known manner and so interlocked with one another to form a closed structure. In order to obtain the requisite curvature, the sheets are slightly bent inwards when being trued up after rolling.

In the construction shown in Figs. 1 and 2 the individual pile members are of box-like section and the several interlocking joints are all disposed on the inner peripheral circle of the closed or hollow structure formed by them. This arrangement gives a particularly strong pile, as will be understood by those skilled in the art.

In the construction shown in Figs. 3 and 4, the individual pile members are all of the same section but adjacent members are arranged in reverse order and the several interlocking joints are disposed along the neutral axis.

Either construction produces a dolphin pile of great mechanical strength yet having the requisite mobility and elasticity to absorb the kinetic energy of vessels moored thereto.

As illustrated in Fig. 5, a hollow pile structure formed in the manner herein described may be filled in with earthy material denoted by the reference *c* and surmounted by a capping *d* which capping holds the mooring devices *e'*. In this figure, the capping is shown as a ferro-concrete capping, and it will be seen that the reinforcing bars thereof are secured to the upper ends of the pile members. The mooring rings *e'* are connected to the upper ends of reinforcing bars *e* embedded in the cap and pile body.

The sphere of application of the invention is unlimited and it will be apparent that dolphin piles for all kinds of purposes can be constructed in accordance therewith.

Having now fully described my invention, what I claim and desire to secure by Letters Patent is:—

1. A dolphin pile comprising a tubular enclosing structure and a filling of earthy material, the enclosing structure being composed of a plurality of similar arched relatively narrow vertically extending sheet

metal pile members arranged to form a circular structure with the convex surfaces of the members outwardly, the members connected at their adjacent edges, and said connections being spaced inwardly from the perimeter of the completed structure, whereby said perimeter is composed of a relatively large number of relatively narrow engaging surfaces providing a protection for the connections.

2. A dolphin pile comprising a tubular enclosing structure and a filling of earthy material, the enclosing structure being composed of a plurality of similar arched relatively narrow vertically extending sheet metal pile members arranged to form a cir-

cular structure with the convex surfaces of the members outwardly, the members connected at their adjacent edges, and said connections being spaced inwardly from the 20 perimeter of the completed structure, whereby said perimeter composed of a relatively large number of relatively narrow engaging surfaces provides a protection for the connections, and a ferro-concrete capping closing the top of the structure and provided with mooring members anchored thereto and to the filling.

25 In testimony whereof I have affixed my signature.

HERMANN OBERSCHULTE.
